TOY GUN

Edward L. Drumheller, Buena Vista, Va.

Application June 4, 1946, Serial No. 674,168

5 Claims. (Cl. 124—27)

1

This invention relates to a toy gun and more particularly to those guns in which a projectile such as a small ball is projected out of the barrel of the gun toward a mark by the impact of a spring-impelled strike-pin or plunger rod.

It is an object of the invention to provide a toy gun of the aforementioned type in which the spring impelling means utilizes little space in the longitudinal direction of the gun, thereby rendering the projectile impelling mechanism particularly adapted for use in pistol type toy guns or relatively short rifle type guns.

It is a further object of the invention to provide a repeater type of toy gun of the aforementioned type in which the force required to compress the spring impelling means is distributed over more than one finger of the star trigger.

Another object of the invention is to provide a toy gun of the aforementioned type in which the spring impelling means, or a part thereof, also functions as a stop to prevent reverse rotation of the star trigger.

Other objects and advantages of the invention will become apparent as the description proceeds, reference being made to the accompanying drawings, wherein:

Fig. 1 is a central longitudinal sectional view of one form of my toy gun.

Fig. 2 is a fragmentary side elevational view of the gun illustrated in Fig. 1, showing one of the cap holding and firing means.

Fig. 3 is a fragmentary sectional view illustrating a modified form of spring impelling means and star trigger stop means.

Fig. 4 is a fragmentary sectional view illustrating a modified form of the means for retaining the ball in the barrel, and a modified form of barrel and handle body construction.

Fig. 5 is a sectional view taken along the line 5—5 of Fig. 1 looking in the direction of the arrows.

Fig. 6 is a sectional view taken along the line 6—6 of Fig. 1 looking in the direction of the arrows.

Fig. 7 is a plan view of the spring illustrated in Fig. 1.

Fig. 8 is a plan view of the star trigger stop member illustrated in Fig. 1, and

Fig. 9 is a sectional view taken along the line 9—9 of Fig. 1 looking in the direction of the arrows.

Referring to the drawing, and first to Figs. 1, 2 and 5 to 9, the toy gun constructed in accordance with my invention therein illustrated comprises a handle 1 integrally connected to a body

2

or handle body 2. The forward end of the handle body 2 is provided with a segmental cylindrical recess 3 which receives the gun barrel 4. The barrel 4 may be glued or otherwise suitably secured to the handle body.

A sight 5 is secured to the forward end of the barrel by means of a dowel pin 6 and glue. The bore 7 of the barrel is provided adjacent its rearward end with a pin 8 projecting thereinto to prevent the balls or other projectiles from rolling rearwardly out of the barrel proper. The upper portion of the rearward end of the barrel 4 is provided with an opening 9 through which the projectiles such as the balls 10 may be fed into the barrel. A curved spring 11 is secured to the barrel by suitable means such as the screw 11' and extends down into the bore 7 of the barrel adjacent the forward end of the recess 9. The spring 11 prevents the ball 10 from rolling forwardly out of the barrel until impelled by the impelling means to be later described.

A magazine 12 is suitably secured to the upper portion of the handle body. The magazine 12 is provided with a downwardly and forwardly inclined passage 13 which communicates with the opening 9 leading into the bore 7 of the barrel 4. A stop plug 14 is provided for the rearward end of the magazine 12. The plug 14 extends into the passage 13 and is preferably held in place by means of a pin 15 extending transversely therethrough and bayonet slot 16 provided in the end of the magazine 12.

The central portion of the handle body 2 is provided with a recess generally indicated by the numeral 17. The recess 17 comprises an upper portion 18 extending entirely across the handle body 2. Below the portion 18 the recess assumes substantially a T-shape (Fig. 9) and this portion of the recess is designated by the numeral 19. The rearward portion of the T-shaped recess 19 is the wider portion. A preferably circular passage designated generally by the numeral 20 is provided in the handle body 2 substantially in alignment with the bore 7 of the barrel 4. The recess 17 divides a circular passage 20 into two longitudinally spaced passages 21 and 22.

A strike-pin or plunger rod 23 is mounted for reciprocation in the passages 21 and 22. The forward end of the plunger rod 23 is suitably recessed as indicated at 23' to permit the rod 23 to pass over the pin 8. A block 24 provided with a passage 25 for receiving the plunger rod 23, is suitably connected to the plunger rod adjacent the central portion thereof by means of pins 26 and 27. The block 24 is located in the upper por-

tion 18 of the recess 17 and reciprocates with the plunger rod 23.

The forward end wall 28 of the upper portion 18 of the recess 17 is provided on each side of the passage 22 with a pistol cap supporting means 29. The caps 30 may be inserted one from each side of the handle body 2. The cap supporting means 29 comprise inwardly directed flanges 29' and may be secured to the wall 28 by screws or other suitable means (not shown). Firing pins 31, Figs. 2 and 5, are suitably imbedded or supported in the block 24 in alignment with the cap supporting means 29. The firing pins 31 project forwardly of the block 24 a distance sufficient to set off the pistol caps 30.

The bottom of the block 24 is provided with a recess 32 through which a pin 33 extends transversely. The pin 33 is engaged by one end of a cam 34 which is pivotally mounted on a pin 35 in the portion 19 of the recess 17. The other end of the cam 34 is engaged by the fingers 36 of a star-shaped trigger 37 which is also pivotally mounted by means of pin 38 in the portion 19 of the recess 17 below the cam 34.

The lower portion of the rearward wall 39 of the recess 17 is curved rearwardly as indicated at 40. A flat leaf power spring 41 and a star trigger stop spring member 42 are secured to the portion 40 of the wall 39 by means of a screw 43. The spring means 41 extends upwardly in the recess 17 and preferably freely engages the rearward end of the block 24. The spring 41 is provided with an elongated opening 44 to receive the rod 23. The elongated opening 44 permits the spring to move transversely relative to the rod 23.

The stop member 42 extends upwardly to the upper rear portion of the finger 36 of the star trigger 37 which will next actuate the cam 34, to prevent reverse rotation of the trigger 37.

A trigger guard 45 may be secured to the bottom of the handle body 2 by suitable means such as the screws 46.

In assembling, the barrel, with the spring 41 and pin 33, is secured to the handle body 2. Then, with respect to the parts located in the recess 17, preferably the cap supporting means 29 are secured to the wall 28 and then cam 34 is pivotally mounted in the recess by the means 35. Next, the spring 41 and the stop member 42 are secured to the lower portion 40 of the wall 39 by means of the screw 43. The spring 41 is then held rearwardly and the block 24, with the firing pins 31 already secured thereto, is placed in the portion 18 of the recess 17 with the pin 33 engaging the rearward side of the cam 34. Next, the plunger rod 23 is inserted in the passage 20 forwardly through the opening 44 in the spring 41 and the opening 25 in the block 24 to a position such that it blocks the feeding of the balls 10 into the barrel 4 through the opening 9 when the block 24 is in its forwardmost position as shown in Fig. 1. The block 24 is then secured to the rod 23 by means of the pins 26 and 27. The star trigger 37 may next be pivotally mounted in the recess 17 by means of the pin 38. Lastly the trigger guard 35 and the magazine 12 are secured to the handle body 2.

In operation, the magazine 12 is filled with projectiles such as the balls 10 in a well known manner. Next, the star trigger 37 is actuated slightly to withdraw the firing pins 31 a short distance rearwardly of the cap supporting means 29. Powder caps may then be inserted in one or both of the cap supporting means 29. Pres-

sure on the trigger may then be released and the gun fired at a later time if desired.

On firing the gun, when the trigger is actuated in a clockwise direction as illustrated in Fig. 1, the cam 34 engaged thereby is actuated in a counter-clockwise direction and by means of the pin 33 the block 24 and the rod 23 connected thereto are actuated rearwardly against the force of the spring 41. In its rearward movement the forward end of the rod 23 passes beyond the opening 9 and a ball 10 drops down into the barrel from the magazine. The pin 8 prevents rearward rolling movement of this ball 10 and the spring 11 prevents forward rolling movement thereof. In its rearward-most position, the forward end of the rod 23 is spaced from the ball 10 positioned between the pin 8 and spring 11.

Just after the trigger is moved clockwise beyond the position indicated in dotted lines in Fig. 1, the trigger finger 36 disengages the cam 34 and the spring 41 thereupon impels the block 24 and the plunger rod 23 forwardly. In its forward movement the rod 23 engages the ball 10 in the barrel and impels it or projects it therefrom. At about the time the ball leaves the plunger rod in the barrel the firing pins 31 strike the powder caps 30 and explode them. This simulates the firing of a real gun since just after the explosion of the powder caps is heard, the ball is projected from the end of the barrel.

It is, of course, obvious that it is not always necessary to operate the gun in the manner just described. The caps may be fired without projecting a ball 10, and similarly, the balls 10 may be projected without firing a pistol cap.

The modification illustrated in Fig. 3 differs from the modification just described in that a second flat leaf power spring 47 is substituted for the stop means 42. The spring 47 is convexly curved forwardly as indicated at 48 and the portion 48 thereof extends into the space between two adjacent fingers 36 of the star trigger 37. These two fingers are, the one which will next actuate the cam 34, and the second one in line for the actuation of the cam 34. The upper end of the spring 47 freely engages the rearward end of the block 24 in substantially the same manner as the spring 41.

Thus, the spring 47 performs a dual function. It assists the spring 41 in driving the plunger rod 23 forwardly, and also, the curved portion 48 acts as a stop means to prevent reverse rotation of the trigger 37.

Also, in this latter modification, the force required to compress the springs 41 and 47 is distributed over the two fingers of the star trigger that the curved portion 48 thereof lies between. One part of this compressive force is transmitted to and carried by the actuating finger 36 of the trigger 37 by the block 24 and cam 34. The other part is transmitted directly to and carried by the next actuating finger 36 by the curved portion 48 of the spring 47. Obviously, any force tending to compress the spring 47 must also necessarily tend to compress the spring 41 located rearwardly thereof, and thus the force required to compress both springs is distributed over two fingers of the star trigger.

The arrangement of the spring impelling means 41 of Fig. 1, and also the similar arrangement of the spring impelling means 41 and 47 of Fig. 3, provides an impelling means which utilizes a minimum of space in the longitudinal direction of the gun, thereby rendering the pro-

jectile impelling mechanism particularly adapted for use in pistol type toy guns or relatively short rifle type guns. Also, due to the utilization of a minimum of space in the longitudinal direction of the gun, the projectile type impelling mechanism described herein is particularly adapted for use in a toy gun utilizing an elongated rotary magazine such as disclosed in my copending application, Serial No. 674,169, filed of even date herewith.

Fig. 4 illustrates a modified form of construction in which the handle body 2 and the barrel 4' are of integral construction. Also, a modified form of means for preventing the projectile from rolling out the forward end of the barrel is illustrated.

This means comprises a recess 49 formed in the forward portion of the magazine 12'. The axis of the recess 49 is downwardly and slightly rearwardly directed, and a relatively small passage 50, preferably coaxial with the recess 49, leads from the bottom of the recess 49 into the bore 7' of the barrel 4'.

A pin 51, having a head 52 thereon resting normally on the bottom of the recess 49, extends downwardly through the passage 50 a short distance into the bore 7' of the barrel 4'.

A plug 53, having a spring 54 secured thereto as by means of a screw 55, closes the recess 49. The plug may be retained in the recess by any suitable means, such as by friction, or the recess 49 and the plug 53 may be provided with screw threads. The spring 54 urges the head 52 of the pin 51 downwardly to normally maintain the pin 51 extending into the bore 7' of the barrel 4'.

The pin 51 projecting into the bore 7' prevents the ball 10 which drops down into the bore 7' of the barrel 4' when the plunger rod 23 is retracted, from rolling forwardly out of the barrel 4' until impelled therefrom by the forward movement of the plunger rod 23. When a ball 10 is so impelled, the pin 51 is retracted momentarily against the force of the spring 54 by the ball 10 passing thereunder.

With the exception of the spring means, firing pins and cap supporting means, which are preferably made of metal, any suitable material such as wood, plastic or metal may be used in the construction of my toy gun.

While the invention is susceptible of various modifications and alternative constructions, I have shown in the drawings and have herein described in detail the preferred embodiments, but it is to be understood that I do not thereby intend to limit the invention to the specific forms disclosed, but intend to cover all modifications and alternative constructions falling within the spirit and scope of the invention as expressed in the appended claims.

I claim:

1. In a toy gun comprising a handle body, a recess in said handle body, a passage in said handle body, a rod mounted for reciprocation in said passage, a block connected to said rod, said block being located in said recess, a plurality of flat leaf power springs extending upwardly in said recess, the lower ends of said springs being secured to said handle body and the upper end of at least one of said springs pressing against the rearward end of said block, an elongate cam pivotally mounted in said recess, one end of said cam engaging said block to actuate the same rearwardly against the force of said one of said springs, a star-shaped trigger pivotally

mounted in said recess, the fingers of said trigger engaging the other end of said cam in turn for actuating the same, and one of said springs extending into the space between two adjacent fingers of said star-trigger, the fingers of said trigger also engaging said last mentioned one of said springs in turn to retract the same.

2. In a toy gun comprising a handle body, a recess in said handle body, aligned passages in said handle body forwardly and rearwardly of said recess, a rod mounted for reciprocation in said passages, a block connected to said rod, said block being located in said recess, a plurality of flat leaf power springs extending upwardly in said recess, the lower ends of said springs being secured to said handle body and the upper ends thereof pressing against the rearward end of said block, an elongate cam pivotally mounted in said recess, one end of said cam engaging said block to actuate the same rearwardly against the force of said springs, a star-shaped trigger pivotally mounted in said recess, the fingers of said trigger engaging the other end of said cam in turn for actuating the same, one of said springs being curved and extending into the space between two adjacent fingers of said star-trigger, the fingers of said trigger also engaging said curved spring in turn to retract the same.

3. In a toy gun comprising a handle body, a recess in said handle body, aligned passages in said handle body forwardly and rearwardly of said recess, a rod mounted for reciprocation in said passages, a block connected to said rod, said block being located in said recess, a flat leaf power spring extending upwardly in said recess, the lower end of said spring being secured to said handle body and the upper end thereof freely engaging the rearward end of said block, an elongate cam pivotally mounted in said recess, one end of said cam engaging said block to actuate the same rearwardly against the force of said spring, a star-shaped trigger pivotally mounted in said recess, the fingers of said trigger engaging the other end of said cam in turn for actuating the same, said spring being curved and extending into the space between two adjacent fingers of said star-trigger, the fingers of said trigger also engaging said curved spring in turn to retract the same.

4. In a toy gun comprising a handle body, a recess in said handle body, a passage in said handle body, a rod mounted for reciprocation in said passage, a block connected to said rod, said block being located in said recess, a plurality of flat leaf power springs extending upwardly in said recess, the lower ends of said springs being secured to said handle body and the upper ends thereof pressing against the rearward end of said block, an elongate cam pivotally mounted in said recess, one end of said cam engaging said block to actuate the same rearwardly against the force of said springs, a star-shaped trigger pivotally mounted in said recess, the fingers of said trigger engaging the other end of said cam in turn for actuating the same, one of said springs being curved and extending into the space between two adjacent fingers of said star-trigger, the fingers of said trigger also engaging said curved spring in turn to retract the same.

5. In a toy gun comprising a handle body, a recess in said handle body, a passage in said handle body, a rod mounted for reciprocation in said passage, a block connected to said rod, said block being located in said recess, a flat leaf power spring extending upwardly in said recess, the

lower end of said spring being secured to said handle body and the upper end thereof freely engaging the rearward end of said block, an elongate cam pivotally mounted in said recess, one end of said cam engaging said block to actuate the same rearwardly against the force of said spring, a star-shaped trigger pivotally mounted in said recess, the fingers of said trigger engaging the other end of said cam in turn for actuating the same, said spring being curved and extending into the space between two adjacent fingers of said star-trigger, the fingers of said trigger also engaging said curved spring in turn to retract the same.
